UNITED STATES PATENT OFFICE.

JAMES T. MALLOY, OF LOWELL, MASSACHUSETTS, ASSIGNOR, BY DIRECT AND MESNE ASSIGNMENTS, OF ONE-HALF TO JOHN J. HENDERSON, OF DRACUT, MASSACHUSETTS, AND ONE-HALF TO SAMUEL R. HAINES, OF BROOKLINE, MASSACHUSETTS.

BOBBIN STRIPPER FOR AUTOMATIC LOOMS.

1,423,670.

Specification of Letters Patent. Patented July 25, 1922.

Application filed March 13, 1920. Serial No. 365,516.

To all whom it may concern:

Be it known that I, JAMES T. MALLOY, a citizen of the United States, residing at Lowell, in the county of Middlesex and State of Massachusetts, have invented certain new and useful Improvements in Bobbin Strippers for Automatic Looms, of which the following is a specification.

This invention relates to what are known 10 as automatic or weft replenishing looms. In order that mispicks may be avoided in weaving, practically every bobbin or weft carrier which is used is discharged from the shuttle or from the magazine with more or less yarn 15 thereon.

In some automatic weft replenishing looms, the shuttles are automatically discharged when the weft is almost exhausted, but in the much more common type, and the type 20 to which my invention is especially applicable, when one bobbin in a shuttle is almost exhausted of weft or filling, it is discharged and another one is replaced in the shuttle. While my invention might be used on shuttle 25 replacing looms, it is more particularly adapted for those in which the bobbins are replaced.

Before the bobbins on which yarn is wound can be used again, the remaining 30 yarn must be removed therefrom. Such removal may be done by hand or by a separate machine, or it may be removed by bringing the loose end in contact with a stripper, such as a revolving spindle or revolving bobbin, 35 which catches such loose end of the yarn and unwinds it from the bobbin while the bobbin is dropping into the can and after it is in the can.

With the last described devices, if 40 loose end of yarn does not engage the stripper, that particular bobbin is not stripped, and if another afterwards descends and its end is caught, it drops into the can and its yarn, as it is being wound up on the stripper, 45 frequently engages the end on an unwound bobbin with the result that two or more bobbins become entangled and are lifted to the stripper, causing jams and serious injuries.

Particularly where the bobbins are re- 50 plenished and the almost empty bobbin is forced out by a full bobbin, there is a tendency, if the shuttle springs are not of ex-

actly the same strength, for the discharged bobbin to start spinning in a direction which winds up the yarn as it goes down, and this 55 tendency is accentuated when it strikes the apron usually provided on such looms.

In practically all such automatic looms, the weft carrier is changed when the lay beam is in contact with or at its nearest 60 point of approach to, the breast beam, while the shuttle starts to traverse when the lay beam is about halfway back to its farthest point from the breast beam.

The yarn on the old bobbin is cut near the 65 cloth leaving a loose end from which the shuttle, with the new bobbin, is supposed to clear itself on the first pick. Frequently however, it carries the old loose end with it into the cloth making side lines and double 70 picks.

The purpose of this invention is to provide a trap which will positively and invariably catch the loose end of yarn between the point where it is cut at the edge 75 of the cloth and the bobbin, and hold it until the shuttle clears itself of the old loose end and until the bobbin or other weft carrier begins to unwind as it descends. Preferably I provide means to assist the bobbin to unwind and I so arrange my trap that it will positively catch and hold the loose end of yarn during certain periods but will release it at other periods to permit the end to clear 80 itself or be cleared from the trap and other 85 parts.

The weft carrier may be unwound or stripped by gravity alone or may be assisted by various devices.

In the drawings, Fig. 1 is a front elevation of part of the breast beam and lay beam of a magazine loom, with my preferred form of device in position, parts being broken away to show the construction.

Fig. 2 is a sectional elevation looking from 90 the right on line 2—2 of Fig 1.

Fig 3 is a side elevation of the parts of a magazine loom, including the lay beam, shown in section, picker stick and the dagger.

Fig. 4 is a diagram in elevation showing 100 three looms on one floor, and the connections with a floor below.

Fig 5 is a sectional side elevation similar to Fig. 2 showing another form of trap.

Fig. 3 is a front elevation showing my trap, together with a revoluble spindle and can, together with certain parts of the loom, to illustrate the operation.

5 Fig. 7 is a side elevation showing parts of a narrow fabric loom, in a position similar to Fig. 3.

Fig. 8 is a horizontal section of a lay beam with a modified form of trap, one position 10 being shown in full lines and another position in dotted lines.

In the drawings, A represents the breast beam, L the lay, 10 part of the frame, C the picker, and 12, 12 the magazine of a magazine loom of the Crompton and Knowles type. 9 represents a full bobbin in the magazine, and B a bobbin which has been almost exhausted of the yarn 13 and has been discharged from the shuttle, such as D, having 20 an eye 19.

21 and 22 represent the opposite walls of the passage 11 in the lay beam L through which the empty or almost empty bobbin is discharged from a shuttle and 20 is the loose 25 end of yarn.

I prefer to locate my trap T in this passage, as shown in Figs. 2 and 3, as it is desirable to catch the end of the yarn 13 as soon as possible after the bobbin has been 30 charged.

My trap T comprises a spindle 30 carried in bearings 23 and 24 shown as attached to the outside of the lay beam on the side 22.

The arms 31 and 32 extend at right angles 35 to spindle 30 preferably so curving that the cross bar 33 will rest snugly up against the top part of side 22 when the trap is closed. This forms a trap bobbin passage 39.

The returning spring 35 is attached at 40 one end to spindle 30 and at the other end to bearing 23, and is so positioned that it tends to fold up the trap against the side 22 when not pushed open by the dagger 36. This dagger 36 is connected at 37 to any stationary 45 part of the frame 10 and passes through a suitable hole 27 in the side 22. The dagger and hole are so positioned that the dagger will strike a bumper plate 34 on arm 31 when the lay beam has almost come up to its 50 nearest point to the breast beam and immediately before the empty bobbin is discharged. The dagger 36 may be rigid, or may be a metal rod which can readily be bent so as to adjust the parts correctly.

55 Preferably, the dagger strikes at a point on the bumper plate pretty well down towards the spindle so that the cross bar 33 will move rapidly over to the dotted line position as shown in Fig. 3. I find that from 60 three-quarters to one inch from the final stationary position of the lay beam is desirable on many looms.

As shown in Fig. 2, my trap is open just before the bobbin is discharged, but is 65 closed by the spring 35, as the lay beam re-

cedes, in time to catch and hold the loose end of the yarn before it is carried past by the descending bobbin.

As soon as the end is caught, the bobbin, being still in flight, will be spun around, 70 unwinding, and, if it has sufficient space in which to drop, all the yarn will be unwound. Instead of the can generally used with such looms, I may use a chute, such as 45, into which the bobbin B drops, continuing down to the 75 floor below or to several floors below, unwinding as it goes until all the yarn is unwound. On the next pick, the trap is again open and the weight of the yarn will clear it from the trap while that is open. The 80 chute may be regarded as means to assist the bobbin to unwind.

I may arrange a plurality of looms, such as 40, 41, 42, standing on floor 43, with chutes 45, 46 and 47 which enter a common 85 chute 48 which terminates in a box 49 resting on the floor below 44. The bobbins will drop through these chutes into box 49. I may also provide a suction pipe 50 connected with a blower 51 whereby powerful currents 90 of air will run down through chutes 45, 46 and 47, which will pick up the unwound yarn and carry it through to the blower or into a suitable receptacle. The empty bobbins meanwhile will remain in the box 49. 95

In such a case, the chutes, box and blower may all be regarded as means to assist the bobbins to unwind.

In Fig. 5, I show a modification of my trap, in which the spindle 61 is hung at the 100 back of side 21 of the lay beam on hangers 60 and has a depending tail 63 in position to be engaged by dagger 64. The arms 62 extend up and in, and they, with the cross bar 65, are normally held up close to the side 105 21 by a suitable spring, not shown. The dagger 64 will open up the trap from the back instead of from the front.

In Fig. 6, as a means to assist the bobbin to unwind, I show a revolving spindle 15 carried in suitable bearings 14 on frame 10, carrying whirl 16 revoluble by a belt 17. This spindle is similar to that shown in reissued patent to Moore, No. 13,119, May 31, 1910, and is so positioned that, as the 110 bobbin B falls, the yarn 13 will come in contact with the revolving spindle and will be wound up thereon.

Under certain conditions it is not necessary to have any means to assist the bobbin 120 to unwind. For instance, I show in Fig. 7 a narrow fabric loom with a breast beam 70 and lay beam 71 to which is attached a small trap, on the same principle as the one shown in Fig. 1, indicated by 72. In such looms 125 there is left on each quill, such as 73, so short a piece of yarn 74 that by the time the quill has reached the bottom of a can, such as 75, the yarn has entirely unwound from the bobbin or quill. Such looms may weave 130

fabric less than one inch wide, in which case quills are used, or somewhat wider, up to twelve or eighteen inches, where bobbins are used, but bobbins and quills are the equivalent so far as this device is concerned.

6 The yarn catcher bar 33 of my trap T is so near the top of the lay beam bobbin passage 11 and my trap is so timed that the loose end 20 is caught as soon as the bobbin 10 has passed through the bobbin passage 39 and before there is much acceleration of its descending speed by gravity.

10 While I prefer the type of trap previously described, wherein there is a catcher bar 15 which catches the yarn close up to the shuttle and wherein there is a bobbin passage 39 between the spindle 30, side arms and catcher bar 33, which is entirely closed in, it is apparent that other types of traps may 20 be used. I find it most convenient to utilize the motion of the lay beam to operate the trap, and to have a dagger or its equivalent so positioned that a slight movement of the lay beam will open the trap widely, and a 25 similar backward movement will close it rapidly. It is important that instead of uncertain means for retarding the loose end, positive trap mechanism should be used which will invariably seize the end.

30 In Fig. 8, I show a modified form of trap M, which is pivoted at 50 to a bracket 49 and extends into the lay beam bobbin passage 11 through a hole 56. It has a short arm 51 on the outside, a rigid main arm 52, and 35 a stiff forearm 53 at a right angle thereto. In extension of forearm 53 is the elastic hand 54 formed of spring metal, leather, or other suitable material, so positioned that, as shown by the full lines, it will normally 40 hug closely the inner side 55 of the front wall 22 of the lay beam. A spring 57 which engages short arm 51 holds it normally in this position, so that when an end 13 is caught, it will be firmly held in place. Fore- 45 arm 53 and hand 54, when the trap M is pushed back by dagger 36, may rest snugly in the groove 58 in the back wall 51. The trap bobbin passage is formed between the arms 52 and 53 and hand 54. As shown in 50 Fig. 1, the yarn 13 running out from the shuttle eye 19 naturally passes down through the end of passage 11 where hand 54 is located. The loose end will thus invariably be caught thereby as the lay beam 55 recedes from the dotted line position to the full line position.

I claim:

1. The combination with a weft replenishing loom having a frame, a breast beam, 60 and a lay beam with a bobbin passage, of a trap comprising side bars pivoted to the lay beam and a cross bar connecting them, leaving a bobbin passage between such cross bar and part of the side bars being located

in the lay beam bobbin passage, a spring 65 adapted to keep the trap normally closed, and a dagger attached to the frame in such position that it will so engage the trap as to open it during part of the period of the lay beam's movement to and from the breast 70 beam.

2. The combination with a weft replenishing loom having a lay beam with a bobbin passage, of a trap having a bobbin passage located in the lay beam bobbin passage, 75 a trap closing spring, and trap opening means adapted to open the trap while a bobbin is passing through the bobbin passage.

3. The combination with a weft replenishing loom having a lay beam with a bobbin passage, of a trap having a bobbin passage located in the lay beam bobbin passage, and means to so operate the trap as to open and close it for different periods. 80

4. The combination with a weft replenishing loom, of means adapted to assist the bobbin to unwind after it is discharged from the shuttle, and a trap located in position to catch the loose end of the yarn and 90 to hold it until the bobbin begins to unwind and to release its hold on the yarn at each beat-up of the lay beam.

5. The combination with a weft replenishing loom having a lay beam with a bobbin passage, of a trap having a bobbin passage located in the lay beam bobbin passage, 95 a trap closing spring, and trap opening means operative by the swing of the lay beam adapted to open the trap while a bobbin is passing through the bobbin passage. 100

6. The combination with a weft replenishing loom having a lay beam with a bobbin passage, of a trap having a bobbin passage located in the lay beam bobbin passage, 105 a trap closing spring, and a dagger so attached to the breast beam as to engage and open the trap while a bobbin is passing through the bobbin passage.

7. The combination with a weft replenishing loom having a lay beam with a bobbin passage, of a trap having a bobbin passage located in the lay beam bobbin passage, trap closing means, and trap opening means operative from the lay beam adapted to 110 open the trap at each swing thereof. 115

8. The combination with a weft replenishing loom having a lay beam with a bobbin passage, of a trap having a bobbin passage located in the lay beam bobbin passage, 120 and means to so operate the trap as to open and close it at each swing of the lay beam, together with means to assist the bobbin to unwind after it is discharged from the shuttle. 125

In testimony whereof I have affixed my signature.

JAMES T. MALLOY.
